United States Patent Office

Des. 186,922

Patented Dec. 22, 1959

186,922

BATTERY OPERATED ERASER

Leonard Streich and Edward S. Atkinson, Houston, Tex.

Application August 9, 1957, Serial No. 47,291

Term of patent 3½ years

(Cl. D74—7)

Fig. 1 is a side elevational view of a battery operated eraser showing my new design;

Fig. 2 is a front elevational view thereof;

Fig. 3 is a top plan view; and

Fig. 4 is a rear elevational view thereof.

We claim:

The ornamental design for a battery operated eraser, as shown.
